Primary Examiner—Cynthia E Ramirez*(74) Attorney, Agent, or Firm*—Renner, Kenner, Greive, Bobak, Taylor & Weber(57) **CLAIM**

The ornamental design for a frame for a mechanic's creeper, as shown and described.

DESCRIPTION

FIG. 1 is a top, rear, left side perspective view of a frame for a mechanic's creeper showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof; and,

FIG. 7 is a rear elevational view thereof.

The broken lines showing the pad and the casters are for illustrative purposes only and form no part of the claimed design.
